UNITED STATES PATENT OFFICE.

EDWARD D. ROCKWELL, OF BRISTOL, CONNECTICUT, ASSIGNOR TO THE LIBERTY BELL COMPANY, OF BRISTOL, CONNECTICUT, A CORPORATION OF CONNECTICUT.

TROLLEY-HARP.

SPECIFICATION forming part of Letters Patent No. 770,113, dated September 13, 1904.

Application filed January 13, 1904. Serial No. 188,902. (No model.)

To all whom it may concern:

Be it known that I, EDWARD D. ROCKWELL, a citizen of the United States of America, residing at Bristol, in the county of Hartford, 5 and State of Connecticut, have invented certain new and useful Improvements in Trolley-Harps, of which the following is a specification.

My invention relates to trolley-harps, and 10 has for its object the provision of an improved device of this character so constructed that the trolley-wheel and its shaft will be capable of a swivel movement with relation to the harp, in combination with means comprising 15 a single member for preventing the accidental displacement of said trolley-wheel.

Further objects and advantages of the invention will be set forth in the detailed description which now follows. 20 In the accompanying drawings, Figure 1 is a longitudinal vertical section of the trolley-harp constructed in accordance with the invention. Fig. 2 is a front elevation of a portion 25 of said trolley-harp. Fig. 3 is a detail view of a yoke hereinafter described. Fig. 4

is a transverse vertical section of the trolley-wheel and its shaft. Fig. 5 is a longitudinal vertical section of a modified form of the device. Fig. 6 is an inverted plan view of a portion 30 of the harp, illustrating a pair of spring-pressed retaining-levers hereinafter described. Fig. 7 is a side elevation of a portion of an extension carried by the yoke shown in Fig. 5, and Fig. 8 is a detail perspective view of one 35 of the spring-pressed levers shown in Fig. 6.

Like numerals designate similar parts in all of the figures of the drawings.

In both forms of the device the numeral 5 indicates a trolley-harp provided with a bore 40 6, in which is secured a rod 7 by pins 8 and 9. This rod may be continued to form a trolley-pole or it may be inserted in the bore of a hollow trolley-pole, as desired. Mounted in ways 10 and 11, formed in the forks of the 45 harp, are bearing-blocks 12 and 13. Bearing-block 12 is formed integral with the trolley-wheel shaft 14, in a bore 15 of which is mounted a spring 16, which bears against a plug 17,

having an extension 18, which in turn bears against the inner wall 13' of bearing-block 13, 50 said bearing-block being recessed at 19 to receive the end of the trolley-wheel shaft 14. To retain the plug 17 in the bore of the trolley-wheel shaft 14, the end of said shaft is spun over, as at 20. An eye 21 is cast upon 55 the harp, to which a trolley-rope may be secured.

Referring now to Figs. 1, 2, and 3, the numeral 22 designates a yoke or fork comprising the base 22' and the upturned arms 22". An extension 23 of said yoke passes through the base of the harp, which is recessed, as at 24, for the reception of a spring 25, which encircles said extension and serves to hold the yoke in its elevated position. A knob or handle 26 is threaded upon the end of extension 23 to enable the operator to withdraw the arms 22" from the paths of bearing-blocks 12 and 13 when desired. A split pin 27 passes through extension 23 and limits the upward 60 movement of the yoke. A guide for the yoke is provided by the ribs 28 and 29, between which the arms 22" lie. 65

Figs. 5, 6, 7, and 8 illustrate a modification of the means for preventing the accidental 70 displacement of the bearing-blocks, said means comprising a yoke 30, having the upturned arms 30' and the extension 30", enlarged at its lower end, and having formed therein cup-like recesses 31, adapted to be engaged by 75 bosses 32, formed upon the outer ends of levers 33, pivoted loosely upon a lug 34, formed upon the base of the harp. A spring 35 forces the inner ends of these levers apart, and consequently presses the bosses 32 into 80 the cup-like recesses 31 to thereby hold the yoke 30 in its elevated position. 85

The operation of the device is as follows: When the car is passing around a curve or from a straight line to a diverging line, the 90 loose mounting of the bearing-blocks 12 and 13 in the ways 10 and 11 permits the trolley-wheel to twist in the forks of the harp, one of the bearing-blocks remaining at the rear end of its way and the other bearing-block 95 riding forward in its way until it abuts

against one or the other of the arms of the yoke, as will be readily understood. Since the trolley-wheel shaft is formed integral with the bearing-block 12, said shaft is thereby held against rotation.

In trolley-harps now in use, in which the trolley-wheel-shaft bearings have been loosely mounted in ways thereof, it has been found that the jolting of the car and the movement of the parts when the car goes around a curve causes arcing to result and the trolley-wheel and its bearings are so badly burned as to be useless. To prevent this and to insure a continuous contact, the arrangement of parts shown in Fig. 4 is provided. As the trolley-wheel assumes various angles with the ways and the bearing-blocks move in or out along said ways the spring 16, acting against plug 17, always forces the bearing-blocks into contact with the walls of their ways.

When the various parts of an electric-railway system are coated with ice and snow, almost continuous arcing results and the trolley-wheels are often so badly burned that it is necessary to remove them and substitute others therefor. The trolley-harp herein shown and described is so constructed that this may readily be done. When it is desired to remove an old wheel and substitute another therefor, knob 26 is grasped by the operator and the yoke 22 drawn downwardly against the tension of spring 25 until the upper ends of the arms 22³ of said yoke are withdrawn from the path of the bearing-blocks. Extension 23 of the yoke is notched, as at 23', said notch being adapted to engage the edge of wall 24', which forms the bottom of recess 24, to hold the yoke in its retracted position while the new wheel is being inserted in the ways of the harp. The yoke is then released and the spring 25 forces it into the position shown in Fig. 1 to thereby prevent the accidental displacement of the trolley-wheel from the ways.

Referring now to the modified form of the device illustrated in Figs. 5, 6, 7, and 8, the yoke 30 is normally held in the position illustrated in Fig. 5 by the levers 33, and when it is desired to insert a new wheel in the ways of the harp the inner ends of said levers are

pressed together, which serves to withdraw 50 the bosses 32 from the recesses 31 and permits said yoke to drop from the path of the bearing-blocks. The extension 30² of the yoke tapers and is larger at its lower end than at its junction with said yoke. By virtue of this 55 construction said yoke is less likely to become jammed by ice or snow than if said extension were of equal thickness throughout its length.

From the foregoing description it will be seen that this invention embodies a trolley-harp so constructed that the trolley-wheel may be readily removed therefrom or inserted therein when desired, and will when mounted in the ways have a swivel movement with relation thereto to thereby accommodate itself 60 to the direction of the trolley-wire with relation to the car in going around curves or in passing from a straight to a diverging track. It will also be seen that means are provided for insuring a continuous contact between the 65 trolley-wheel-shaft bearings and the harp and that means comprising a single element have been shown and described for preventing the accidental displacement of said trolley-wheel.

While the elements shown and described are well adapted to serve the purposes for which they are intended, it is to be understood that changes may be made in the details thereof if desired.

What I claim is—

1. The combination, with a trolley-harp having ways, of trolley-wheel bearing-blocks mounted in said ways, a stop member adapted to be thrown into or from the path of said blocks and means for locking said member in its retracted position.

2. The combination, with a trolley-harp having ways open at one end, of a spring-actuated yoke normally closing the open ends of said ways and means for locking said yoke in its 90 retracted position.

In testimony whereof I affix my signature in presence of two witnesses.

EDWARD D. ROCKWELL.
